United States Patent Office

Des. 183,334
Patented Aug. 5, 1958

183,334

HYGROMETER

Ralph C. Wappner, Springfield, Ohio, assignor to The Ohio Thermometer Company, Springfield, Ohio, a corporation of Ohio

Application May 11, 1956, Serial No. 41,450

Term of patent 14 years

(Cl. D52—7)

Fig. 1 is a perspective view of a hygrometer embodying my new design;

Fig. 2 is a front view thereof;

Fig. 3 is a side view thereof; and

Fig. 4 is a rear view thereof.

I claim:

The ornamental design for a hygrometer, substantially as shown.
